CLAIM

The ornamental design for a display device, as shown and described.

DESCRIPTION

FIG. 1 is a perspective view of the display device in a fully folded state;

FIG. 2 is a front view thereof;

FIG. 3 is a rear view thereof;

FIG. 4 is a left side view thereof, with the right side view being a mirror image thereof;

FIG. 5 is a top view thereof;

FIG. 6 is a bottom view thereof;

FIG. 7 is a perspective view of the display device in a half-folded state;

FIG. 8 is a front view thereof;

FIG. 9 is a rear view thereof;

FIG. 10 is a left side view thereof, with the right side view being a mirror image thereof;

FIG. 11 is a top view thereof;

FIG. 12 is a bottom view thereof;

FIG. 13 is a perspective view of the display device in a fully unfolded state;

FIG. 14 is a front view thereof, with the rear view being a mirror image thereof;

FIG. 15 is a left side view thereof, with the right side view being a mirror image thereof;

FIG. 16 is a top view thereof;

FIG. 17 is a bottom view thereof;

FIG. 18 is a perspective view of the display device in a folded and slid state;

FIG. 19 is a front view thereof;

FIG. 20 is a rear view thereof;

FIG. 21 is a left side view thereof, with the right side view being a mirror image thereof;

FIG. 22 is a top view thereof;

FIG. 23 is a bottom view thereof; and,

(Continued)

FIG. 24 is a perspective view thereof with an image displayed on the screen of the display device in the folded and slid state. The image is shown for reference only and forms no part of the design.

The broken lines shown in the drawings are included for the purpose of illustration and form no part of the claimed design.
